UNITED STATES PATENT OFFICE.

CALEB E. SUMMERS AND FOREST H. HARTZELL, OF DAYTON, OHIO.

THERMOSTATIC REGULATOR.

Application filed November 28, 1924. Serial No. 752,821.

Our invention relates to thermostatic regulators for explosive engines and more particularly to an automatically operated valve controlling the admission of air to the carburetor of a hydrocarbon engine particularly of the automotive type.

The present device is not to be confused with automatic air valves commonly known as "economizers" ordinarily connected with the intake manifold intermediate the carburetor and inlet port of the engine cylinder. The present automatic valve is located in advance of the carburetor in the normal air supply conduit. It is customary to admit air to the carburetor thru a supply conduit extending in proximity to the exhaust conduit of the motor whereby the air supply is initially warmed. The present invention pertains to the regulation of this normal or initial supply of air rather than to the supplying of a supplemental or auxiliary supply additional to such initial and normal air supply as in the case with the typical economizer. In the present instance the air intake conduit leading to the carburetor is provided with a valve of the butterfly type controlled by a thermostatic blade exerting push and pull influence upon the valve tending to close such valve at low temperature and to progressively open the valve to admit a greater quantity of air as the temperature of the engine increases. Thus during cold weather or when the engine is initially started at which time a richer fuel mixture is required the thermostatic valve is tensioned toward closed position thereby restricting the admission of air and allowing a greater proportion of fuel to be drawn from the carburetor. After the engine is in operation and its temperature increases the thermostatic control device tends to open such air valve to admit increasing quantity of air affording a more lean mixture.

In the present instance the control valve and the thermostatic regulator are mounted in a supporting frame forming a unit insertable within and removable from the air supply conduit thereby enabling the regulator to be easily and readily applied to existing motors.

The object of the invention is to simplify the construction as well as the means and mode of operation of thermostatic regulating devices for motors, whereby they will not only be cheapened in construction, but will be more efficient in operation uniform in action

automatically controlled and unlikely to get out of repair.

A further object of the invention is to provide a unitary device including the mounting for the valve and the thermostatic control member, capable of being detachably engaged within the air supply conduit.

With the above primary and other incidental objects in view as will more fully appear in the specification, the invention consists of the features of construction the parts and combination thereof, and the mode of operation or their equivalents as hereinafter described and set forth in the claims.

In the drawings, Fig. 1 is a side elevation of a typical automobile motor showing the relative location of the air supply conduit and the automatic regulating valve forming the subject matter hereof mounted therein. Fig. 2 is a vertical sectional view of a portion of the air conduit and of the thermostatic regulator located therein. Fig. 3 is a rear elevation of the regulator mounted within the air intake conduit. Fig. 4 is a perspective view of the regulator viewed from the side opposite that shown in Fig. 3.

Like parts are indicated by similar characters of reference thruout the several views.

In the drawings 1 is the typical automobile motor of which 2 is the intake manifold, 3 the carburetor to which the intake manifold 2 is connected and 4 the air supply conduit leading to such carburetor. The intake orifice of the air supply conduit 4 is located in proximity to the exhaust manifold 5, so that the air supply is preheated as it enters the air supply conduit 4. This is a typical automobile motor construction and per se forms no part of the present invention. The present thermostatic regulator is located in the air supply conduit 4, which is more or less closed thereby so long as the engine is cold and is opened to admit air more freely, by the automatic adjustment of the valve as the engine temperature increases.

The regulator comprises an oscillatory valve 6 actuated to and fro by a thermostatic blade 7. While the oscillatory valve 6 might be pivoted directly into the walls of the air conduit 4 and the control member 7 suitably mounted upon such wall the valve and thermostatic blade are preferably mounted upon a removable frame or support 8. The mounting or support 8 comprises a channel shaped frame member having side flanges 9 and 10.

having in its intermediate web portion a comparatively large opening 10 within which is pivoted the oscillatory valve 6. The valve 6 comprises a plate of elliptical form which will 5 conform closely to the walls of the air conduit 4 when in an inclined or diagonal position. The valve plate 6 is medially indented in opposite directions to form a hinge connection thru which extends a trunnion pin 11, 10 secured in ears 12, at the opposite sides of the mounting.

Secured to the bottom of the mounting 8 is a thermostatic blade 7, the upper free edge of which is engaged beneath a keeper 13 upon 15 the valve plate 6. This keeper 13 may be a loop of wire or the like, brazed or otherwise secured to the valve plate, but for economy of construction and simplicity of manufacture, such keeper 13 is preferably a loop of 20 material formed integral with the valve plate by being struck up from the plane of the plate between two parallel transverse slits. The end of the thermostatic blade 7 is slightly bent forwardly into a partial hook formation 25 which engages beneath the keeper 13, the thermostatic blade 7 in one direction of its deflection bears against the valve plate 6 below the hinged connection thereof, thereby turning the valve plate about its pivotal connection into closed position. Upon the reverse deflection of the thermostatic blade, 30 the pressure of the blade against the keeper 13 tends to turn the valve plate 6 about its horizontal axis of oscillation in the opposite direction and into the plane of the support or 35 mounting and parallel with the air conduit, thereby opening the air conduit for the admission of maximum air supply. The thermostatic blade thus exerts alternate push and 40 pull influence upon the oscillatory valve plate 6.

To prevent transverse warping and distortion of the thermostatic blade 7, the latter is 45 preferably longitudinally slit into a plurality of tongues or fingers, which however, operate in unison as a single integral thermostatic member.

The natural tendency of the thermostatic blade 7 when cold is to exert pressure against 50 the valve plate 6 tending to turn the plate to a diagonal position in which the air conduit 4 is closed. As the engine temperature increases, and the thermostatic blade 7 is subjected to warping or deflection by such 55 increase of temperature it exerts a pulling influence upon the loop or keeper 13, tending to turn the valve plate 6 progressively into parallel relation with the conduit.

In order to detachably support the regulating unit within the air supply conduit 4, one 60 of the flanges 9 of the mounting is extended to form a reversely bent finger or hook 14, which engages over the end of the conduit 4 to suspend the unit. The remaining ends of 65 the side flanges 9 of the mounting are pro-

vided with spring fingers 15, which yieldingly engage the interior walls of the conduit 4 to frictionally retain the units therein and prevent rattle or chatter. To the same end the reversely bent finger 14 is provided 70 with a light flexible spring extension 17, yieldingly engaging the exterior of the conduit 4.

The regulating device is readily installed 75 by sliding it longitudinally into the open end of the air intake conduit 4, wherein it occupies a central position with the reversely bent suspension finger 15 overhanging the top margin or end of the conduit, with the spring fingers 15 and 17 yieldingly engaging the walls of such conduit to maintain the unit in its adjusted position.

The valve 6 is normally diagonally positioned within the conduit, restricting the admission of air until the engine is in operation 80 and the engine temperature increases whereupon the deflection of the thermostatic blade will progressively open the valve to its full extent, thereby admitting the maximum air supply. 85

Due to the fact that the trunnion pin 10 is offset slightly out of the exact medial plane of the conduit, the axis of oscillation of the valve plate 6 is eccentric or spaced a less distance from the top of the valve than from the bottom edge thereof, affording an unbalanced valve. When the engine is speeded up, a greater amount of air is necessary to afford a proper combustible mixture with the correspondingly greater amount of fuel. 90 If the engine is so speeded or raced when yet cold, the unbalanced feature enables the valve to open under the increased suction, against the tension of the thermostatic blade, to permit the required proportionate quantity 95 of air to reach the carburetor. 100

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages. 110

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention, is therefore, claimed in any 120 of its forms or modifications within the legitimate and valid scope of the appended claims. 125

Having thus described our invention, we claim: 130

1. As an article of manufacture, a thermostatically operated regulating device comprising a valve plate medially hinged for oscillatory movement, a supporting frame in which the valve plate is mounted, a keeper loop carried by the valve plate in offset relation with the axis of oscillation, and a thermostatic blade having one end fixedly secured to the supporting frame and the other end loosely engaged beneath said keeper loop and by its deflection exerting alternately push and pull influence upon the valve plate to open the valve under temperature increase, close the same under decrease of temperature.
2. As an article of manufacture, a thermostatically operated regulating device, a valve, a thermostatic member actuating the valve, a mounting for said valve, and thermostatic member comprising a frame removably insertible within a conduit pipe or the like, a hook on said frame for engagement over a wall of the conduit, and a plurality of spring fingers carried by the frame for yielding engagement with the conduit walls.
3. In a regulator for explosive engines, a valve plate pivoted in the air supply conduit leading to the carburetor of an explosive engine, the valve being of greater weight at one side of its axis of oscillation than at the other, a thermostatic spring within said air supply conduit exerting both push and pull influence upon the valve plate, the valve being adapted to yield against the tension of the thermostatic spring and independent of temperature change under influence of the engine suction.
4. In a regulating device for explosive engines, a regulating valve located in the air supply conduit leading to the carburetor of an explosive engine, a thermostatic control member for said valve comprising, a spring blade longitudinally slitted to afford a plurality of parallel fingers acting simultaneously upon said valve to adjust the valve in accordance with variations of temperature.
5. In a regulating valve for explosive engines, a medially pivoted valve plate located in the air supply conduit leading to the carburetor of an explosive engine, the axis of oscillation of the valve being so located that the area of the valve at one side of such axis is greater than at the other, and a thermostatic control spring actuating the valve under variations of temperature within said air supply conduit, said valve plate being further subject to the influence of the engine suction acting upon the portion of said valve plate of greater area to actuate the plate contrary to the influence of the thermostatic spring and independent of temperature changes.
6. In a construction of the character described, a supporting frame insertible within an air conduit, a damper valve pivoted in said frame, a keeper loop carried by the valve, and a thermostatic blade mounted upon the frame and having its free end engaged in said keeper loop to actuate the damper in alternate directions in accordance with variations of temperature of air passing through the conduit.

In testimony whereof, we have hereunto set our hands this 15th day of November, A. D. 1924.

CALEB E. SUMMERS.
FOREST H. HARTZELL.
